(57) **CLAIM**

(**) Term: **15 Years**

The ornamental design for a window component extrusion,
as shown and described.

(21) Appl. No.: **29/544,379**

DESCRIPTION

(22) Filed: **Nov. 3, 2015**

FIG. 1 is a perspective view of a window component
extrusion according to the present invention.

(51) **LOC (10) Cl. 25-01**

FIG. 2 is a right side view of the window component
extrusion of FIG. 1.

(52) **U.S. Cl.**

FIG. 3 is a left side view of the window component extrusion
of FIG. 1.

USPC **D25/124**

FIG. 4 is a front view of the window component extrusion
of FIG. 1.

(58) **Field of Classification Search**

FIG. 5 is a rear view of the window component extrusion of
FIG. 1.

USPC D25/119-125, 60; D20/42, 43, 44
CPC E06B 1/36; E06B 2003/26321; E06B
3/26345; E06B 1/702; E06B 1/366; E06B
1/04; E06B 1/28; E06B 1/30

FIG. 6 is a top view of the window component extrusion of
FIG. 1; and,

See application file for complete search history.

FIG. 7 is a bottom view of the window component extrusion
of FIG. 1.

(56) **References Cited**

The window component extrusion is shown with two parallel
dash-dot lines and a bracket to represent indeterminate
length. The appearance of any portion of the article between
the break lines forms no part of the claimed design.
